UNITED STATES PATENT OFFICE.

CLAUDIUS DORNIER, OF FRIEDRICHSHAFEN, GERMANY.

HULL OF FLYING MACHINES.

Application filed June 28, 1920. Serial No. 392,552.

To all whom it may concern:

Be it known that I, CLAUDIUS DORNIER, a citizen of Germany, residing at Friedrichshafen, Germany, have invented certain new and useful Improvements in Hulls of Flying Machines, of which the following is a specification.

My present invention relates to flying machines and more especially to the hull or body of such a machine and is intended to satisfactorily solve the problem of housing the power plant in the case of flying machines provided with a plurality of motors and propellers, respectively. In the case of flying machines of this kind, it has always been considered as a very serious drawback that those portions of the power plant lodged outside of the hull are only rendered accessible with great difficulty. The result is that engine cars of rather large size have had to be constructed, as the accessibility thereto by way of the planes forms a problem which can only be solved successfully in the case of big flying machines having four or even more than four motors of the strength at present in use, while in the case of smaller types of flying machines this would result in practically impossible plane sections being constructed. Moreover the degree of accessibility which can be easily effected does not comply with all requirements.

If thus up to now there always existed considerable difficulties of properly tending the motors, this drawback has become still more apparent in connection with single deck aeroplanes, a type of flying machines more and more acknowledged as being extremely favorable. For in this particular construction the transmission of the landing forces owing to the weight of the power plant, caused extreme trouble. For while the said forces in the case of multiple deck aeroplanes of advantageous construction, and having a plurality of motors, are immediately transferred to the carriage, a simple and direct transmission of this kind can not be readily obtained in the case of more or less self-supporting single deck flying apparatus, as the plane, which is already subject to great strains, must then be made specially strong at its seat, i. e. at the place where it is joined to the hull.

My present invention is intended to ob-

viate all these drawbacks by not only providing a ready accessibility to the motors, and an advantageous transmission of power, but, in addition, by offering the possibility of reinforcing the plane by means of stays having a favorable angle of application. These advantages are obtained by the hull or body being provided at its sides with disk-shaped hollow extensions forming an integral part thereof, and which are intended to house either the entire power plant or the driving gear only, as may be desired, and which at the same time shall serve as a stay or support for the more or less self-supporting wings. Having regard to the advisability of arranging the motors or the driving gear close to the hull proper, the said hollow disk-shaped members possess, in accordance with my invention, but a slight depth, with the result that the hull will obtain approximately the cross-section of an inverted T.

By these means the entire motor plant or, where this is arranged in the center, merely the laterally located driving gear may either entirely or partly be lodged on or within the disk-shaped hollow extensions, so that said parts of the driving mechanism will be constantly and readily accessible, while, on the other hand, the carriage may be easily arranged in such wise that it will be able to take up directly the forces transmitted. Moreover by fixing stays to the extremities of the disk-shaped hollow extensions there is obtained an essential reduction in height of the wing joists, and consequently, a favorable wing section. Further advantages reside in the fact that the wings may be supported at a relatively great width by aid of stays having a very favorable angle, and that further, the forces may be taken up advantageously by the laterally disposed hollow bodies of the hull and thus directly transmitted on to the carriage.

In the accompanying drawings forming part of this specification, the preferred form of a structure embodying the subject matter of my invention is clearly illustrated.

In the drawings—

Fig. 1 discloses a front elevation of the improved hull structure as applied to a monoplane;

Fig. 2 is a front elevation,

Fig. 3 a side elevation and

Fig. 4 a plan of a part of the hull drawn to an enlarged scale.

The monoplane shown in Fig. 1 consists of a body or hull 1, having lateral hollow extensions 2 on which the covered motors 3 are so lodged as to be accessible from the interior of the hull. The plane 4 which extends right across the entire structure is connected at the center to the hull and laterally supported or stayed by stays 5. The wheels 6 of the carriage are disposed immediately below the motors 3.

In Figs. 2, 3 and 4 the hull is indicated by 7. On the disk-shaped hollow extensions 8 are mounted motors 9, covered so as to offer the least possible resistance to the air. The two motors drive two traction propellers 10, and project somewhat forwards beyond the lateral bodies. The stays 11 serve to support the plane (not shown).

Although the subject matter of my invention is intended in the first line for single deck flying machines provided at each side with one, or it may be a plurality of motors, it is however equally applicable in respect of multiple deck machines. In the case of large sized flying machines, one complete carriage, comprising one or more sets of wheels, will be found to be required for each side, said carriages being then arranged

symmetrically to each power plant. Or the power plant may also be located centrally, i.e. all the motors may, if desired, be housed in the hull proper, only the driving gear (bevel-wheel gear, or the like), being disposed on the outside and lodged on or within the hollow extensions.

I claim:—

1. Flying machine comprising in combination a hull the middle portion of which has a cross-section resembling a hollow inverted T and driving gear on the lateral portions of said hull. 40

2. Flying machine comprising in combination a hull the middle portion of which has a cross-section resembling a hollow inverted T, driving gear on the lateral portions of said hull and a supporting plane braced against said lateral portions. 45

3. Flying machine comprising in combination a hull the middle portion of which has a cross-section resembling a hollow inverted T and a motor on each lateral portion of said hull. 50

4. Flying machine comprising in combination a hull the middle portion of which has a cross-section resembling a hollow inverted T, a motor on and a carriage below each lateral portion of said hull. 55

In testimony whereof I affix my signature.
CLAUDIUS DÖRNIER.
